CLAIM

The ornamental design for a face guard, as shown and described.

DESCRIPTION

FIG. 1 is a perspective view of a face guard showing my new design; the straps removed for convenience of illustration;

FIG. 2 is an enlarged front elevational view thereof;

FIG. 3 is a right side elevational view thereof;

FIG. 4 is a bottom plan view thereof;

FIG. 5 is a top plan view thereof;

FIG. 6 is a rear elevational view thereof; and

FIG. 7 is a cross-sectional view taken along line 7—7 of FIG. 2.

The face guard straps are broken away in FIGS. 3, 5, 6 and 7 for convenience of illustration
